GARMENT BAG CARRIER

James G. Peters, 1 Penrose Lane,
Colorado Springs, Colo. 80906

Filed Aug. 23, 1971, Ser. No. 174,290

Term of patent 14 years

Int. Cl. D8—03

U.S. Cl. D8—154

FIG. 1

FIG. 2

FIG. 3

FIG. 4

FIG. 5

FIG. 1 is a rear elevational view of a garment bag carrier embodying my new design;

FIG. 2 is a side elevational view;

FIG. 3 is a front elevational view;

FIG. 4 is a perspective view; and

FIG. 5 is an enlarged, fragmentary view showing the hanger hook portion.

The broken lines in FIGS. 4 and 5 are for illustrative purposes only.

I claim:

The ornamental design for a garment bag carrier, substantially as shown and described.
